UNITED STATES PATENT OFFICE.

DAVID W. R. MORGAN, OF SWARTHMORE, PENNSYLVANIA, ASSIGNOR TO WESTINGHOUSE ELECTRIC AND MANUFACTURING COMPANY, A CORPORATION OF PENNSYLVANIA.

LARGE JET CONDENSER.

Application filed December 3, 1920. Serial No. 428,059.

To all whom it may concern:

Be it known that I, DAVID W. R. MORGAN, a citizen of the United States, and a resident of Swarthmore, in the county of Delaware and State of Pennsylvania, have invented a new and useful Improvement in Large Jet Condensers, of which the following is a specification.

My invention relates to jet condensers, particularly those of relatively large size, and has for its object to provide apparatus of the character designated which shall be flexible in its operating characteristics and which, at the same time, shall be relatively compact in size and economical in material for the capacity involved.

In the accompanying drawing, Fig. 1 is a side view partially in section and partially in elevation of a condenser embodying my invention, together with an associated turbine and auxiliary apparatus; and Fig. 2 is a plan sectional view of Fig. 1 taken on the line II—II of Fig. 1.

In connection with steam turbines of extremely large size, it has been customary to provide what are known as twin jet condensers, that is to say, two jet condensers of more or less standard design being supplied, thus caring very efficiently for the double discharge of the turbine of the double flow type and at the same time providing vapor and water interconnections capable of relieving each other to a certain extent. By this means, continuity of service has been secured, and at the same time, condensers of more or less standard form have been provided to care for turbines of unprecedentedly large size.

However, installation and operation of two condensers of this type is very expensive because of duplication of many elements that might well be combined, and I, therefore, propose to combine the inlet chambers and the mixing chambers of the two condensers into one large condenser, preferably, elliptical in plan section and I may further provide two independent water and air removal outfits for this consolidated condenser structure, thereby providing the flexibility and continuity of service secured with the two independent condensers, but at the same time securing a cheaper mixing

chamber and a more effective distribution of condensable and non-condensable vapors.

Not only does the elliptical plan section of the inlet chamber lend itself more readily to the usual shape of the turbine base, but also a more effective spray distribution is secured therein than would be possible in a circular inlet chamber of large diameter, all as will hereinafter be more fully pointed out.

Referring to the drawing for a more detailed understanding of my invention, I show a condenser aggregate 5 at Fig. 1, this aggregate comprising an inlet chamber 6 and water box 7 having nozzles 8 directed into the chamber 6, a mixing chamber 9 and condensate pumps 10 and 11.

The inlet chamber 6 is preferably elliptical or elongated in plan section, as shown more clearly in Fig. 2 and thus conforms itself to the shape of the base of the exhaust casings of a turbine 12, shown as of the double flow type. Furthermore, by forming the inlet chamber 6 of elliptical or elongated shape, the necessary main free path of the condensing water jets from the nozzles 8 is radially reduced as compared to that required for means disposed in a circular inlet chamber of the same capacity.

A mixing chamber 9 mounted beneath the inlet chamber 6 may be of elliptical cross section, as shown, or it may convert to the circular shape, either within itself or by the use of special adapter. The mixing chamber further carries the usual baffle member 13 to permit the accumulation of non-condensable gases thereunder, these gases being removed by air ejectors or other form of air pump 14 and 15 of any usual or desired type through air removal conduits 16 and 17.

At its lower end the mixing chamber 9 is constructed to form a throat 18 and a bifurcated discharge member 19 is disposed beneath, leading the condensate to the condensate removal means 10 and 11, the latter being shown as centrifugal pumps, although pumps of other types adapted for this use may also be used. A conduit 20 interconnects the lower portions of the bifurcated parts of the member 19, thus insuring equality of load upon the two condensate pumps when both are operating, and

insuring the flow of all condensate to either pump when it alone operates.

Having thus described the condenser embodying my invention, the operation is as follows: Exhaust steam flows from the turbine 12 into the inlet chamber 6 and there encounters the sprays projected from the nozzles 8. By the use of an inlet chamber of an elliptical plan view, a reduced amount of water is required and a relatively low degree of vacuum suffices to maintain sufficient head on the nozzles to cause the sprays to fill the whole of the inlet chamber. Thus slight differences in the degree of vacuum as brought about by different loads on the turbine, different temperatures of cooling water, and defects in the operation of the air removal means, are ineffective in interfering with the distribution of the sprays within the inlet chamber, as would be the case were this inlet chamber of circular view and of equal capacity as the attendant necessary of relatively long sprays.

Moreover by employing a common inlet chamber, the necessity for pressure-equalizing connections between the inlet chambers of the twin-unit condensers, now commonly used with turbines of the double flow type, is eliminated and consequently both the length and the area of the connections between the turbine and condensers can be materially reduced.

The condensate rains down through the baffle 13 and, under full load conditions, is divided by the bifurcated member 19 and one-half thereof is ejected by each of the condensate pumps.

Under conditions of light load, but one set of auxiliaries may be operated, the non-condensable gases readily flowing across the large mixing chamber provided and all condensate passing either directly or through the conduit 20 to the one condensate pump in operation.

In the event that one set of auxiliaries is disabled, by overloading the remaining set, the full load on the turbine may be approximated.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. A jet condenser, comprising a single mixing chamber, a plurality of water removal pumps arranged to operate in parallel to eject water therefrom, and connection means between the pumps to equalize the loads carried thereby.

2. A jet condenser, comprising a single

mixing chamber, a plurality of independently actuated water removal pumps arranged to operate in parallel to eject water therefrom, and connection means between the pumps to equalize the loads carried thereby.

3. A jet condenser, comprising a single mixing chamber, a plurality of water removal pumps arranged to operate in parallel to eject water therefrom, and means for controlling the distribution of water to said pumps.

4. A jet condenser, comprising a single mixing chamber of elliptical plan section, a plurality of water removal pumps arranged to operate in parallel to eject water therefrom, and means for controlling the distribution of water to said pumps.

5. In a jet condenser, means providing a single mixing chamber of elongated plan section, and spray nozzles arranged in the wall thereof, whereby the spray travel of each nozzle for effective condensation is less than would be the case with a similarly arranged mixing chamber of circular plan section.

6. In a jet condenser, means providing a single mixing chamber of elongated plan section, spray nozzles arranged in the wall thereof, whereby the spray travel of each nozzle for effective condensation is less than would be the case with a similarly arranged mixing chamber of circular plan section, and a plurality of water-removal pumps and of air-removal devices arranged to draw from said mixing chamber.

7. In a jet condenser, means providing a single mixing chamber of elongated plan section, spray nozzles arranged in the wall thereof, whereby the spray travel of each nozzle for effective condensation is less than would be the case with a similarly arranged mixing chamber of circular plan section, and a plurality of independently driven water-removal pumps and of independently driven air removal devices arranged to draw from said mixing chamber.

8. A jet condenser for a double-flow turbine comprising a single-mixing chamber, separate inlet connections from each end of the double-flow turbine to the mixing chamber, a well into which the liquids from the mixing chamber collect, and means for removing said liquids.

9. A jet condenser for double-flow turbine comprising a single-mixing chamber of elliptical plan section, an inlet connection from each end of the double-flow turbine to the mixing chamber, and spray nozzles arranged in the walls of the mixing chamber, whereby the spray travel from each nozzle for effective condensation is less than would be the case with a like capacity chamber of circular plan section.

10. A jet condenser for a double-flow turbine comprising a single mixing chamber of

elliptical plan section, an inlet connection from each end of the double-flow turbine to the mixing chamber, spray nozzles arranged in the walls of the mixing chamber, whereby the spray travel from each nozzle for effective condensation is less than would be the case with a like capacity chamber of circular plan section, and a plurality of independently actuated water removal pumps arranged to operate in parallel to eject water therefrom.

In testimony whereof, I have hereunto subscribed my name this 30th day of November, 1920.

D. W. R. MORGAN.
